TOILET DEODORIZER

Charles T. Foster, Overland, Mo.

Application May 9, 1947, Serial No. 746,999

2 Claims. (Cl. 4—228)

2

1
This invention relates to improvements in a deodorizer particularly adapted for use in water closet flush tanks of the types now generally employed.

An object of the invention is to provide a container particularly well adapted for disc-like cakes of deodorant and disinfectant and of a shape which will not obstruct the inflow and exit of water used as an afterfill following a flushing operation of the flush tank.

Another object is to provide such a container with a closure which permits the ready insertion of a deodorant cake and inspection of the container, which also confines the water path through the container rather than to permit some of it to flow over into the flush tank and prevent rapid evaporation of the deodorant as occurs in the open.

Another object of the invention is to provide a deodorant container in the afterfill water conduit through which the water flows so that it will not run out when the toilet is flushed but is retained and so as to flow into the bowl as the tank is filling up thereby effecting a saving of the deodorant and providing a more effective afterfill.

Another object of the invention is to provide a relatively flat deodorant container which will fit in flush tanks below the flush tank cover and properly comply with all plumbing regulations and health requirements.

Further objects, details and advantages of my invention will appear in the following detailed description, of the preferred embodiment of my invention taken in connection with the accompanying drawings, forming a part thereof and illustrating a deodorizer which has proven highly satisfactory in practice being simple to install and effective in saving the deodorant material.

In the drawings:

Fig. 1 is a vertical sectional view of a "high" type of flush tank with a deodorizer, in accordance with my invention, applied thereto.

Fig. 2 is a similar fragmentary section of a "low" type flush tank showing the application of the deodorizer.

Fig. 3 is a plan view of the deodorizer container with its lid removed.

Fig. 4 is a vertical sectional view thereof taken substantially on line 3—3 of Fig. 3.

Fig. 5 is a horizontal sectional view taken on line 4—4 of Fig. 4 showing a detail of the adjustable supporting clamp for the container.

Referring to the drawings, Fig. 1 illustrates a high type of flush tank 10 having the usual fittings, flush valve 11 with its overflow pipe 12,

water pressure inlet pipe 13, a float operated valve 14 which is considerably below the top of the overflow pipe 12 and outlet pipe 15 for filling the flush tank. In place of the afterfill pipe which usually extends from the float operated valve into the overflow pipe 12, valve 14 is provided with a short vertically extending pipe 16 which may replace the usual afterfill pipe or only a portion thereof, the portion extending to the overflow pipe being cut off, and connected by a pipe or tube 17 of rubber or the like with the deodorizer 18.

The "low" type flush tank shown in Fig. 2 is of the same general construction except that valve mechanism 14a is in a higher plane with respect to the top of the overflow pipe 12a, making it necessary to dispose the deodorizer 18 in much higher position above the overflow pipe 12a than in the "high" type flush tank shown in Fig. 1.

20 The deodorizer 18, and details thereof illustrated in Figs. 3, 4 and 5, is a preferred highly satisfactory form, being a relatively flat receptacle 19 with upwardly extending side walls providing a generally triangular structure in plan, with 25 rounded corners particularly adapted for a disc-like cake 20 of deodorant leaving relatively large spaces at portions of the side of the deodorant cake to accommodate water from an inlet pipe 21 in one of the spaces and free entrance of water 30 into an outlet pipe 22 in another space, which are beyond the deodorant cake, so as not to be obstructed for inflow and exit of the water.

Referring to Fig. 4 it will be seen that inlet pipe 21, which as shown in Figs. 1 and 2 is connected with pipe 16 by a more or less flexible tube 17, is comparatively small being subject to flow of water under some pressure from valve mechanism 14. Container 19 is provided with a downwardly extending female nipple 23 into which a

40 larger diameter and much larger outlet pipe 22 is threadedly received thus providing an outlet which will allow the water in container 19 to freely pass therefrom into overflow pipe 12, or 12a, as shown in Figs. 1 and 2.

45 Threaded nipple 23 above the upper end of pipe 22 also provides a mounting for flaring coil spring 24 of non-rusting material, the convolutions of which are slightly spaced and provide a protector or strainer to hold pieces of the deodorant cake from passing and a slight deterrent to the flow of water from the container.

The deodorant cake 20 is protected from the air, and likewise the container closed to prevent the overflow of water from the container into the 55 flush tank, by means of a cover 25 the sides 26

of which are shaped corresponding with the shape of the side walls of container 19. As shown the sides 26 flare slightly inward and when inserted in the side walls of container 19, as shown in Fig. 4, provide an effective seal for the purpose. It has been found that a cake of the deodorant used in air will disappear in about a month due to evaporation but in comparison according to tests, a cake in the container will last about three months.

As shown in Figs. 4 and 5 a clamp member 27, adjustable along outlet pipe 22, provides a sturdy mounting for the deodorizer, in a low position as shown in Fig. 1 or a high position as illustrated in Fig. 2, in both cases well below the plane of the top of flush tank 10, or 10^a. Clamp 27 has a depending element 28 closely adjacent to outlet pipe 22 so that when the deodorizer is installed in the flush tank, the upper portion of the overflow pipe 12, or 12^a will be straddled and gripped between the two and thereby hold the deodorizer in proper position in the flush tank.

It will be seen that I have provided a deodorizer which may be quickly assembled in any typical flushing apparatus and while I have described a preferred and highly satisfactory form of deodorant container, I do not want to be limited to particular form or shape thereof as obviously other forms clearly fall within the scope of my invention.

I claim:

1. A deodorizer for water closet flush tanks of the high or low type or the like including the usual water supply and afterfill flushing and valve and overflow pipes mechanisms, said deodorizer comprising a container for cake type of deodorizing material so shaped as to provide spaces beyond the peripheral edges of a deodorant cake when placed therein, a cover for the top of said container substantially sealing the same as a closure for the deodorant cake, inlet conduit connecting means between the bottom of the container communicating therewith in one of said spaces beyond the peripheral edges of the cake and the afterfill of the water supply valve of the flush tank, an outlet pipe of substantially larger diameter than that of said inlet conduit extending downwardly from the deodorant container communicating therewith in another of said spaces beyond the peripheral edges of the deodorant cake, and a vertically adjustable clamp

on the outlet pipe below the container for securing the outlet pipe in the flush tank overflow pipe with the deodorant container in a vertically adjusted position above the same.

- 5 2. A deodorizer for water closet flush tanks of the high or low type or the like including the usual water supply and afterfill flushing and valve and overflow pipes mechanisms, said deodorizer comprising a container for cake type of deodorizing material so shaped as to provide spaces beyond the peripheral edges of a deodorant cake when placed therein, a cover for the top of said container substantially sealing the same as a closure for the deodorant cake, inlet conduit connecting means between the bottom of the container communicating therewith in one of said spaces beyond the peripheral edges of the cake and the afterfill of the water supply valve of the flush tank, an outlet pipe of substantially larger diameter than that of said inlet conduit extending downwardly from the deodorant container communicating therewith in another of said spaces beyond the peripheral edges of the deodorant cake, a strainer extending from the upper end of said outlet pipe upwardly in the container preventing pieces of the deodorant cake from passing from the container and slightly deterring the flow of water therefrom, and a vertically adjustable clamp on the outlet pipe below the container for securing the outlet pipe in the flush tank overflow pipe with the deodorant container in a vertically adjusted position above the same.
